[57] CLAIM

The ornamental design for a planar concrete anchor, as shown and described.

DESCRIPTION

FIG. 1 is a perspective view of a first embodiment of a planar concrete anchor showing our new design;

FIG. 2 is a right side elevational view of the first embodiment;

FIG. 3 is a front elevational view of the first embodiment;

FIG. 4 is a top plan view of the first embodiment;

FIG. 5 is a bottom plan view of the first embodiment;

FIG. 6 is a perspective view of a second embodiment of a planar concrete anchor showing our new design;

FIG. 7 is a right side elevational view of the second embodiment;

FIG. 8 is a front elevational view of the second embodiment;

FIG. 9 is a top plan view of the second embodiment; and,

FIG. 10 is a bottom plan view of the second embodiment.

The left side and rear elevational views of the first embodiment are mirror images of the right side and front elevational views, respectively, of the first embodiment.

The left side and rear elevational views of the second embodiment are mirror images of the right side and front elevational views, respectively, of the second embodiment.
